UNITED STATES PATENT OFFICE.

HERBERT C. COY, OF CHICAGO, ILLINOIS.

COMBINATION LOCK.

Application filed March 29, 1926. Serial No. 98,057.

This invention relates to improvements in combination locks, having a plurality of tumblers in the form of disks, which are free to revolve in either direction and adapted to be 5 rotated into and out of engagement with a suitable keeper, said tumblers requiring separate adjustment for opening the lock.

One of the important objects of this invention is to provide an improved form of 10 combination or permutation lock which responds equally to the sense of sight, hearing or touch, and which, therefore, is especially available for many uses, particularly for mailboxes, and also for doors, drawers, 15 lockers, desks, safes, chests, or the like.

Still another and further important object of this invention is the provision, in a permutation lock, of means for readily changing the combination thereof with a 20 minimum expenditure of time and labor, having at the same time the organization of the operating parts of the lock with the object of providing a simple, compact, inexpensive, but reliable box structure.

25 Other and further important objects of the invention will be apparent from the disclosures in the accompanying drawings and following specification.

The invention, in a preferred form, is illustrated in the drawings and hereinafter more 30 fully described.

In the drawings:

Figure 1 is a front elevation of the improved permutation lock of this invention.

35 Figure 2 is a sectional view, taken on the line 2-2 of Figure 1.

Figure 3 is a detail view of one of the operating tumblers.

Figure 4 is a perspective view of the other 40 operating tumbler.

Figure 5 is a detail view of the operating knob.

Figure 6 is a plan view of the pointer or indicator.

45 Figure 7 is a top plan view of the device shown in Figure 5.

Figure 8 is an end view of the locking nut.

Figure 9 is a plan view of the lock washer, and

50 Figure 10 is a vertical elevation of the key used for disassembling the lock and changing the combination.

Figure 11 shows the means for preventing undesired tumbler movement.

55 As shown in the drawings:

The reference numeral 12 indicates gener-

ally a portion of a door panel or the like to which the lock is applied, the locking tumblers or discs normally extending below the lower or one outer edge of the door. Certain 60 portions of the discs are cut away to permit opening of the door in an obvious manner when the discs are turned into correct position.

The plate 14, provided with a series of 65 numbered notches, is attached to the outer face of the door by means of rivets 16 or the like, and mounted to operate in this plate is a rotatable dial 18 having a pointer 20 thereon as shown in Figures 1, 2, and 6. The rotatable dial is moved by means of a manually operated knob 22 mounted on the end of an operating pin 24, which extends completely through the lock and projects at the rear end thereof as best shown in Figure 2. The stem 70 24 is hexagonal in shape, as shown in Figure 7, and fits into a twelve-sided opening in the plate 18 and also into a similar opening in the first disc 26.

A sleeve 28 surrounds the stem 24 adjacent the knurled knob 22 and by means of a helical spring 30 is pushed into proper positioning relation to the plate or dial 18.

The second disc 32 has a circular hole in the center thereof so as to move freely with 85 relation to the stem 24, and is provided with an inwardly projecting element 34 which contacts with an outwardly projecting pin 36 on the tumbler 26, so that at certain portions of the travel of the disc 32 the disc 26 will 90 be carried along therewith.

A washer 38 is positioned between the tumblers so as to eliminate friction, the tumblers being held in position by means of an overhanging plate 40, the ends of which extend downwardly past the discs and are soldered, riveted, or otherwise secured to the rear face of the plate 12. A spring 56 prevents 95 undesired motion of the rear tumbler.

A locking nut 42 is screw threaded onto the end of the stem 24 and co-operates with a lock washer 44 which is provided with an integral projecting key 46 adapted to be set in a corresponding slot in the stem 24. The locking nut 42 is tapered or frustro conical so as to 100 eliminate any possibility of its being turned by means of any pliers or wrenches, and notches 50 are formed in its outer face which are adapted to receive projecting lugs 52 integral with an operating key 54, whereby 105 the lock may be disassembled and the combination changed at will.

The notches in the plate 14 are deep enough to securely retain the pointer 20 of the dial 18 when the same is moved and the tension of the spring 30 produces a definite click each 5 time the pointer passes over a notch so that the lock may be readily operated in the dark and even by a blind person, providing the combination is known.

The number of the notches, the hexagonal 10 stem, and the relation of the tumblers to the stem and to each other produce a practically infinite number of combinations, and further, the lock is fool proof and also proof against tampering, while at the same time being readily operated by anyone knowing the combination.

I am aware that many changes may be made and numerous details of construction varied throughout a wide range without deviating from the principles of this invention, 20 and I therefore do not purpose limiting the patent granted hereon otherwise than as necessitated by the prior art.

I claim as my invention:

- 25 1. In a permutation lock, the combination of a plurality of circular discs, each having a segment removed therefrom, an operating pin for rotating one of said discs, means on the discs for imparting motion from one to 30 the other at certain portions of their movement, a dial mounted to rotate with the disc operating means, a pointer extending radially beyond the dial, a notched indicator in which said pointer rides, spring controlled 35 means for maintaining said dial in desired position and producing audible sounds upon movement of the pin in the notches, a com-

bined rear support and bearing for the operating pin, and a locking nut and washer fixed on the pin bolt, said rear support to maintain 40 all the parts in co-operative relation.

2. In a permutation lock, the combination of a plurality of circular discs, each having a segment removed therefrom, an operating pin for rotating one of said discs, means on the discs for imparting motion from one to the other at certain portions of their movement, a dial mounted to rotate with the disc operating means, a notched indicator for the dial, spring controlled means for maintaining said dial in desired position and producing audible clicks upon movement, a combined rear support and bearing for the operating pin, and a locking nut and washer fixed on the pin bolt, said rear support to maintain 45 all the parts in co-operative relation, said lock nut being of frustro conical shape.

3. In a combination lock, the combination of a plurality of locking discs, an operating spindle peripherally supporting the discs, one of said discs having a central twelve-sided opening in which said spindle fits in a plurality of determined positions, a knurled operating knob on the spindle hexagonal in cross-section, a pointer removable from but movable with the spindle, a notched dial over which said spindle is movable, and resilient means for maintaining the pointer in co-operative relation with the notches in the dial, and to produce audible sounds upon movement of the pointer over said notches.

In testimony whereof I affix my signature

HERBERT C. COY
